SEED DISPLAY STAND

Albert Edward McKenzie, Brandon, Manitoba,
Canada

Application November 13, 1933, Serial No. 697,727

2 Claims. (Cl. 211—130)

The invention appertains in particular to a display stand for exhibiting packet seeds, and more particularly to the class of stand in which tiers of pockets or compartments are furnished 5 one above another on a backward angle so that the vignette of the foremost packets of each tier are substantially visible.

The salient feature of the invention is to produce a stand of this nature that in itself is inconspicuous by reason of the prominence it gives 10 to the seed packets. This is achieved by so constructing the stand that the goods displayed serve to substantially conceal it.

A further distinctive object is to furnish a display structure that occupies little floor-space in order that the merchant may be able to stack or store other goods under or behind it and thus 15 make good use of available floor room in his store.

20 A still further object is to provide a stand that has a large display capacity and is attractive in appearance and economical to manufacture.

With these main objects in view the invention 25 consists in the novel construction and arrangement of parts as hereinafter described in detail and claimed in the appended claims.

Referring to the accompanying drawing; Figure 1 is a side elevation of the invention showing 30 in dot and dash lines the folded position of a rear leg.

Figure 2 is a rear elevation of Figure 1.

Figure 3 is a front elevation thereof.

Figure 4 is an enlarged vertical sectional view 35 depicting side lugs on the stand that support the inclined trays in which the seed packets are arranged.

Like numerals of reference indicate corresponding parts in each of the figures throughout the drawing of the invention.

40 The drawing is illustrative of the preferred construction of the invention and in carrying this out a pair of inturned angle iron members 6, 6 are provided. The members are sharply inclined for the major part of their length so as to furnish lateral sustaining ledges 7 for seating the trays or containers 8. The lower portions 9 of these members however extend vertically and constitute front legs.

45 The members 6, 6 are rigidly secured to each other by a lower crosspiece 10 and an upper crosspiece 11 both of angle iron. The lower crosspiece has one of its flanges upstanding in order to form a ledge or seat against which the bottom tray or container is shouldered. The 50 upper crosspiece is preferably located at a short

distance from the upper ends of the members 6, 6 and is riveted or otherwise secured to the underside thereof so as not to interfere with the ledges.

With a view of imparting rigidity to the structure, a pair of braces 12, 12 have an end made fast to the respective upper ends of the members 6, 6 and their other ends similarly secured to the crosspiece 11 medially of its length.

With a view of imparting rigidity to the structure, a pair of braces 12, 12 have an end made fast to the respective upper ends of the members 6, 6 and their other ends similarly secured to the crosspiece 11 medially of its length.

55 A very distinctive feature of the invention resides in the construction and arrangement of the rear support which is in the nature of a single leg 13 positioned medially of the width of the stand. This consists of a pair of flat bars 14 secured together at their lower ends at 15 and bent in upwardly diverging directions. The upper ends 16, 16 of these bars are pivoted at 17, 17 to the crosspiece 11 by means of clips 18 so as to be free to fold inwardly.

50 The bars are spaced apart at their juncture 75 15 by means of a filler piece 19 in order to accommodate an arm 20 which is pivotally connected by the rivet 21. This arm is pivoted at 22 to a like arm 23 similarly connected to a clip 24 medially secured on the lower crosspiece 10. 80

It will be evident that the arms maintain the leg in its extended position and that by upwardly folding them, the leg is swung into a collapsed position indicated at A in Figure 1.

65 A set of three trays or containers are utilized 85 and transversely extended, each being seated one above another on the ledges formed by the side members 6, 6 and the lower crosspiece 10. The trays or containers have vertical sides 25 and are interiorly divided into pockets or compartments 26 arranged in tiers for the packets of seeds to be displayed. To preclude dislodgment of the intermediate and upper tray lugs 27 are riveted to the side members 6, 6 so as to engage the front face of the respective trays and thus 90 prevent them from sliding downwardly (see particularly Figure 4). The upper tray may be fitted with a backboard 28.

95 It will be apparent that this construction provides a sturdy and light in weight collapsible stand 100 which is rendered inconspicuous by the trays of seeds prominently displayed. It is understood that incidental changes in construction and arrangement of parts may be resorted to as coming within the spirit and scope of the appended 105 claims.

What I claim is:—

110 1. A display stand of the class described consisting of a pair of inturned angle iron members inclined for the major part of their length and

vertical for the other part of their extent to form legs, the inclined parts of the members presenting ledges for seating trays, a lower angle iron crosspiece disposed at the juncture of the inclined parts of the side members with the legs, said crosspiece presenting a ledge for shouldering the lowest tray, an upper crosspiece rigidly secured to the side members in the vicinity of the upper ends thereof, lugs attached to the side members to preclude dislodgment of the trays, a single leg swingably attached to said upper crosspiece, and a pair of pivotally connected arms, one of which is pivoted to said leg in the vicinity of its lower end and the other of which is pivoted to the aforesaid lower angle iron crosspiece.

2. A display stand of the class described consisting of a pair of inturned angle iron members inclined for the major part of their length and vertical for the other part of their extent to

form legs, the inclined parts of the members presenting ledges for seating trays, a lower angle iron crosspiece disposed at the juncture of the inclined parts of the side members with the legs, said crosspiece presenting a ledge for shouldering the lowest tray, an upper crosspiece rigidly secured to the side members in the vicinity of the upper ends thereof, braces fixed thereto and to said side members, lugs attached to the side members to preclude dislodgment of the trays, a leg composed of a pair of bars united in spaced relation at their lower ends and laterally diverging in an upward direction, the upper ends of the bars being pivoted to the crosspiece, and a pair of pivotally connected arms, one of which is pivoted intermediate of the spaced bars and the other of which is pivoted to the aforesaid lower crosspiece.

ALBERT EDWARD MCKENZIE.
